COMPARTMENT BOX FOR CAPSULES OR
THE LIKE

Johanna Fluss, Hanauerstrasse 30d, Munich, Germany

Filed Nov. 23, 1959, Ser. No. 58,429

Term of patent 14 years

(Cl. D58—13)

FIG.1

FIG.3

Fig. 1 is a top plan view of a compartment box for capsules or the like showing my new design, seen in closed position;

Fig. 2 is a side-elevational view of Fig. 1;

Fig. 3 is a perspective view thereof in open position. The capsules shown in broken lines in Fig. 3 are for illustrative purposes only.

I claim:

The ornamental design for a compartment box for capsules or the like, substantially as shown and described.
